UNITED STATES PATENT OFFICE.

ERNEST S. EKSTROM, OF ROSHOLT, SOUTH DAKOTA.

LATCH.

1,345,913.

Specification of Letters Patent.

Patented July 6, 1920.

Application filed August 21, 1918. Serial No. 250,801.

To all whom it may concern:

Be it known that I, ERNEST S. EKSTROM, a citizen of the United States, residing at Rosholt, in the county of Roberts and State 5 of South Dakota, have invented certain new and useful Improvements in Latches, of which the following is a specification.

This invention relates to improvements in door latches and one object is to provide a 10 simple practical device of this class that is cheap to manufacture and efficient in operation. With the foregoing and other objects in view the invention consists in the combination and arrangement of parts to be 15 hereinafter fully described, pointed out in the appended claim and illustrated in the accompanying drawing which forms a part of this specification and in which—

Figure 1 is a plan view of the latch.

20 Fig. 2 is a cross section taken on line 4—4 of Fig. 1.

Like reference characters denote corresponding parts throughout the several views.

25 The reference numeral 1 denotes a door provided in the wall 2. I provide a bracket 3 secured to the wall 2 and to said bracket the hasp 4 is secured by the hinge 5, the hasp being formed with the usual perforation 6.

I provide a spring 14 upon the hinge pin 15 which spring yieldingly forces the hasp 4 inwardly or toward the wall 2. The angle piece 7 is formed with a pair of ears 15 which are connected by the pin 16 upon which the curved bolt 17 is fulcrumed, the short end of said bolt forming a heel 18 and the longer end of said bolt being adapted for disposal in the perforation 8 of the angle piece 7. To unfasten the door the free 40 end of the hasp 4 is moved outwardly and

in this movement it will contact with the longer end of the bolt 17 and disengage the same from the perforated portion of the angle piece 7 and move the said bolt into 45 the position shown dotted in Fig. 2. The door can now be opened. To fasten the door again, it is closed, and the hasp simply moved into engagement with the angle piece 7. This movement of the hasp causes it to 50 engage with the heel 18 of the bolt 17 and right the bolt or move it again into the position shown in full lines, Fig. 2, thus engaging it again with the perforated end of the said angle piece. The necessity of direct 55 manual movement of the bolt is obviated in this form of latch as the bolt movement is controlled automatically by the hasp movement.

What is claimed is:—

60 In a latch, an angle piece having one end secured to a support and its free end perforated, ears formed upon the non-perforated end of said angle piece, a bolt fulcrumed to said ears and having a long and a short end, 65 the long end of said bolt being adapted for engagement with the perforated end of said angle piece, and a swinging hasp adapted for releasable engagement with the free end of said angle piece, said hasp engaging with 70 the long end of said bolt while moving in one direction and engaging with the short end of said bolt while moving in the opposite direction.

75 In testimony that I claim the foregoing as my own I have hereto affixed my signature in the presence of two subscribing witnesses.

ERNEST S. EKSTROM.
